UNITED STATES PATENT OFFICE

JAMES J. VANHORN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

REMOTE CONTROL APPARATUS

Application filed April 22, 1929. Serial No. 357,013.

My invention relates to remote control apparatus, and is particularly suitable for, though not limited to, noncoded current control of railway traffic governing devices, such as signals and switches, from a distant point.

One feature of my invention is the provision of means for controlling signal indication means over the wires of switch and signal control circuits.

I will describe two forms of apparatus embodying my invention, and will then point out the novel features thereof in claims.

15 In the accompanying drawings, Fig. 1 is a diagrammatic view showing one form of apparatus embodying my invention. Fig.

20 2 is a diagrammatic view showing modifications of the apparatus shown in Fig. 1, and also embodying my invention.

Similar reference characters refer to similar parts in both views.

Referring first to Fig. 1, the reference characters 1 and 1a designate the track rails of a stretch Y of main railway track connected with a siding Z by means of a switch F. Switch F may be operated to one position or the other by any suitable means such, for example, as an electric motor. Switch F, when in its normal position as shown, directs traffic over stretch Y only, and when reversed, directs traffic over stretch Y to or from siding Z. A circuit controller A is operated by switch F, and has two contacts 64 and 122 which are closed while switch F is in its normal position only, and two contacts 154 and 157 which are closed while switch F is in its reverse position only. A circuit controller contact 20 is also operated in conjunction with switch F, and is closed at all times except for a brief period just after the beginning and a second brief period just before the end of each operation of switch F from one extreme position to the other.

Stretch Y is divided by insulated joints 2 into sections C—D and D—E. Each of these sections is provided with a track circuit which is supplied with current by a battery 3 connected across the rails adjacent

one end of the section. Track relays R1 and R2 are connected across the rails adjacent the opposite end of sections C—D and D—E, respectively. Relay R1 is provided with stick control by a circuit which includes 65 one of its own front contacts in multiple with a back contact of relay H1. A slow-releasing relay P is controlled by relay R2.

Signal arms, designated by the reference characters S1, S2, S3, and S4, and which, as here shown, are of the semaphore type, govern movements of traffic over switch F. Arms S1 and S2, adjacent location C, govern eastbound moves, that is, moves toward the right, as shown in the drawing, over 65 switch F normal or reversed, respectively. Arms S3 and S4, mounted on a common mast adjacent location D, govern westbound moves over switch F normal or reversed, respectively. 70

The circuits for operating switch F to its reverse and its normal positions are controlled by contacts 159b and 159a, respectively, of a slow-releasing polarized relay G1, but, since they form no part of my present invention, these circuits are omitted from the drawing. The circuits for operating signal arms S are controlled by a slow-releasing polarized relay H1, the arms for eastbound moves being governed by 80 polar contacts of this relay when closed to the left, and the arms for westbound moves being governed by the polar contacts when closed to the right. Signal arms S are also selectively controlled by circuit controller A which is operated by switch F. 85

Switch control relay G1 and signal control relay H1 are controlled by manually operable levers V1 and V2, respectively, which may be grouped with other similar levers in some suitable location, such, for example, as a train despatcher's office.

Lever V1 has a normal position *n* and a reverse position *r*, and operates two contacts 14 and 146 which are closed when lever V1 is in its *n* or *r* positions, respectively. Lever V2 has a normal position *m*, and a reverse position *p* shown to the left, and a second reverse position *r* shown to the right of position *m*. Lever V2 operates 95

100

contacts 108 and 45 which are closed only when lever V2 is in its *p* position; contacts 148 and 118 which are closed only when lever V2 is in its *r* position; and contact 135 which is closed only when lever V2 is in its *m* position.

5 A signal indication relay N is controlled by signal-operated contacts 5, 6, 7 and 8 which are closed when all arms S are in their "stop" position, respectively. Relays N and R1 together control a slow-releasing stick relay K.

10 An indication relay G2 is operated by current flowing through the windings of relays G1 and G2, switch circuit controller contact 20, and a front contact 17 of track relay R1, in series. A slow-releasing relay *g* is controlled by relay G2.

15 Indication relays designated H2 and L are operated by current flowing through the windings of these relays in series with each other and with the winding of relay H1. Relay L is so constructed as to be responsive only to current of greater magnitude than is necessary for the operation of relays H1 and H2. Current of sufficient magnitude to operate relays H1 and H2 but not relay L is supplied through contacts operated by lever V2. A branch path controlled 20 by relays R2, H1 and P, or a second branch path controlled by relays R2, H1, P and K, or a third branch path controlled by relays N and K, is at times closed around the winding of relay H1, thus permitting sufficient 25 current to flow through the winding of relay L to operate relay L.

30 A stick relay T has a pick-up circuit which is controlled by a contact operated by relay L, a second stick relay X has a pick-up circuit which is controlled by relays L and H2 and by a third stick relay J, and relay J has a pick-up circuit which is controlled by relays H2 and X. A slow-releasing relay W is energized by current flowing 35 through a front contact of relay *g* while stick relays T and X are deenergized.

40 Indicator lamps, designated by the reference character *e* with distinguishing suffixes, are located adjacent levers V1 and V2. 45 Lamp *e*1 is controlled by relay *g*, and serves to inform the despatcher as to traffic conditions within section C—D. Lamp *e*2 is controlled by relay G2, and indicates the operation of switch F by becoming de-energized 50 momentarily upon the opening of switch contact 20 at the beginning and at the end of the operation of switch F. Lamps *e*3 and *e*4 serve to indicate the clearing of an eastbound or a westbound signal, respectively. Lamp *e*5 is controlled by relay T, and serves as an approach indicator to inform the despatcher when an approaching 55 train enters section D—E.

60 Two sources of current, here shown as batteries Q1 and Q2, supply current to the

line circuits and to the local circuits adjacent levers V1 and V2. A third source of current, shown as battery Q3, supplies energy for local circuits adjacent switch F. A fourth source of current, shown as a battery Q4 located adjacent switch F, supplies current for energizing indication relay L in the tower when lever V2 is in its *m* position.

65 Referring to Fig. 2, modifications of the apparatus controlled by lever V2 and of the apparatus for controlling indicator lamps *e*3, *e*4 and *e*5 are here shown. It is assumed that stretch Y, switch F, and signals S are arranged as shown in Fig. 1, and that lever V1 controls circuits as shown 70 in Fig. 1. It is also understood that relays, N, P, and R2 are controlled as shown in Fig. 1. Relays H1, H2 and L are also operated by current flowing in series through these relays as in Fig. 1. Slow-releasing 75 relay U is controlled by relay N. The branch paths around the winding of relay H1 differ slightly from paths shown in Fig. 1, and will be described in detail hereinafter. Stick relays T1 and T2 are provided with 80 pick-up circuits which are controlled by relay L, and the stick relays J, T, and X and slow-releasing relay W of Fig. 1 are omitted. In Fig. 1, stick circuits for relays T and X and the operating circuit for relay W are 85 controlled by a contact of relay *g* but, in Fig. 2, a push button *b* controls the stick circuit for relay T2.

90 Having thus described, in general, the arrangement and location of the various parts comprising my invention, I will now describe the operation of the apparatus.

95 As shown in the drawings, all parts are in their normal condition, that is track sections C—D and D—E are unoccupied, levers V1 and V2 are in their normal positions, switch F is in its normal position and all signals are indicating "stop". With the track sections unoccupied, relays R1 and R2 are energized. The pick-up circuit for relay R1, passing from rail 1 of section C—D goes through wire 69, contact 70 of relay H1, wire 71, and the winding of relay R1 to rail 1a of section C—D. The stick circuit for relay R1 includes its contact 192 in multiple with wires 69 and 71 and contact 100 70. It is clear that both the pick-up and the stick circuits for relay R1 are closed. With relay R2 energized, relay P is energized by its circuit passing from terminal B of battery Q3, through contact 4 of relay R2, and the winding of relay P to terminal O of battery Q3. With all signal arms in the stop position, relay N is energized by current flowing from terminal B of battery Q3, through contacts 5, 6, 7 and 8 which are 105 operated by arms S4, S3, S2 and S1, respectively, wire 9, and the winding of relay N to terminal O of battery Q3. With relays N and R1 energized, the pick-up cir- 110

cuit for relay K is closed, passing from battery Q3, through wire 66, contact 67 of relay N, wires 68 and 198, contact 194 of relay R1, wire 195, and the winding of relay K to terminal O of battery Q3. With relay K thus energized, the stick circuit for relay K is also closed, passing from battery Q3, through wire 66, contact 67 of relay N, wire 68, contact 72 of relay K, and the winding of relay K to terminal O.

With lever V1 in its normal or *n* position, relays G1 and G2 are energized by current flowing from battery Q1, through wires 10, 11, 12 and 13, contact 14 of lever V1, wire 15, winding of relay G2, wire 16, contact 17 of relay R1, wire 18, winding of relay G1, wire 19, switch contact 20, and wires 21, 54, 55, 56 and 22 back to battery Q1. With relay G2 energized, relay *g* is energized by current flowing from battery Q1, through wires 10, 11 and 24, contact 25 of relay G2, wire 26, winding of relay *g*, and wires 27 and 28 back to battery Q1. With relay G2 energized, current is also supplied for lighting lamp *e2* by a circuit passing from battery Q1, through wires 10, 11, 12, 29 and 30, contact 31 of relay G2, wire 32, lamp *e2*, and wires 33 and 28 back to battery Q1. With relay *g* energized, lamp *e1* is also lighted by current passing from battery Q1, through wire 10, contact 34 of relay *g*, wire 35, lamp *e1*, and wires 36, 33 and 28 back to battery Q1. With relay *g* energized and relays T and X de-energized, relay W is energized by current flowing from battery Q1, through wire 10, contact 37 of relay *g*, wires 38 and 87, contact 39 of relay T, contact 40 of relay X, wire 41, winding of relay W, and wires 42, 43 and 22 back to battery Q1.

I will now assume that with all parts of the apparatus shown in Fig. 1 thus in their normal condition, the despatcher desires to clear arm S3 for a traffic movement along stretch Y over switch F in its normal position. He therefore reverses lever V2 to its *p* position. With lever V2 in its *p* position, relays H1 and H2 become energized by current flowing from battery Q1, through wires 10, 11, 12, 29 and 44, contact 45 of lever V2, wire 46, winding of relay H2, wires 47 and 48, winding of relay L, wires 49 and 50, contact 51a of relay P, contact 52a of relay R2, wire 53, winding of relay H1, and wires 54, 55, 56 and 22 back to battery Q1.

Relay H1 now closes its polar contacts in the reverse direction, completing a circuit for arm S3 passing from battery Q3, through wire 57, contacts 58 and 59a of relay G1, wire 60, contacts 61 and 62b of relay H1, wire 63, contact 64 of switch circuit controller A, wire 65, and the operating mechanism of arm S3 to terminal O of battery Q3. Relay H1, upon becoming energized, completes its stick circuit which in-

cludes, around contacts 51a and 52a of relays P and R2, respectively, and wire 53 in the pick-up circuit already traced for relay H1, a branch path comprising wire 116 and contact 117 of relay H1.

Arm S3 moves to its proceed position, thereby deenergizing relay N by opening contact 6. Relay K, being slow-releasing, does not at once open its front contacts when its pick-up and stick circuits are opened by contact 67 of relay N. A branch path around the winding of relay H1 is therefore closed for a brief period of time, passing from wire 50, through wire 73, contact 74 of relay N, wire 75, and contact 76 of relay K to wire 56.

During this brief period, sufficient current flows through the winding of relays H2 and L to energize relay L which, by closing its front contact 78, completes the pick-up circuit for relay T passing from battery Q1, through wires 10, 11, 12, 29, 30, 77 and 91, contact 78 of relay L, winding of relay T, and wires 80, 43 and 22 back to battery Q1. Relay X also becomes energized by current passing from battery Q1 through wires 10, 11, 12, 29, 30, 77 and 91, contact 81 of relay L, wire 82, contact 83 of relay H2, wire 84, contact 85 of relay J, wire 86, winding of relay X, and wires 43 and 22 back to battery Q1. Relay X, upon become energized, completes its stick circuit which passes from battery Q1, through wire 10, contact 37 of relay *g*, wire 38, contact 88 of relay H2, wire 89, contact 90 of relay X, winding of relay X, and wires 43 and 22 back to battery Q1. Relay W becomes de-energized by the opening of contacts 39 and 40 of relays T and X, respectively, but on account of being slow-releasing, relay W does not open its front contacts until after the lapse of a brief period of time following such de-energization. Meanwhile, relay T becomes de-energized on account of relay L becoming de-energized.

With relays H2 and X energized, relay J also becomes energized by current flowing from battery Q1, through wires 10, 11, 12, 29, 30 and 77, contact 92 of relay H2, wire 93, contact 94 of relay X, wire 95, winding of relay J, and wires 42, 43 and 22 back to battery Q1. Relay J, upon becoming energized, completes its stick circuit by closing its contact 97 in multiple with contact 94 of relay X. Relay J, also upon becoming energized, opens its contact 85 in the pick-up circuit for relay X which, however, continues energized by its stick circuit. With relay X energized, lamp *e4* is lighted by its circuit passing from battery Q1, through wires 10, 11, 12, 29, 30, 77, 91 and 105, contact 106 of relay X, wire 107, contact 108 of lever V2, wire 109, lamp *e4*, and wires 103, 33 and 28 back to battery Q1.

If now, a westbound train approaches and

de-energizes relay R2, relay P being of a slow releasing type does not at once open its front contacts, and hence a branch path around the winding of relay H1 is momentarily closed passing from wire 50, through contact 128 of relay P, wire 127, contact 126 of relay R2, wire 125, contact 129 of relay K, wire 130, contact 131a of relay H1, and wire 132 to wire 55. Relay L now again becomes operated by the increased current permitted by the reduction of resistance in series with its winding through the branch path just described. Relay T then becomes energized by its pick-up circuit previously traced, and, upon becoming energized, completes its stick circuit passing from battery Q1, through wire 10, contact 37 of relay g, wires 38, 87, 110 and 111, contact 112 of relay W, wire 113, contact 98 of relay T, winding of relay T, and wires 80, 43 and 22 back to battery Q1.

With relay T thus energized, lamp e5 is lighted by current flowing from battery Q1, through the stick circuit just traced for relay T as far as wire 113, thence through wires 99 and 100, contact 101 of relay T, wire 102, lamp e5, and wires 103, 33 and 28 back to battery Q1. Both signal indication lamp e4 and approach lamp e5 continue energized, until the train enters section C—D de-energizing relay R1 which in turn de-energizes relay G2 which then de-energizes relay g. Relay g, upon becoming de-energized, opens its contact 34, thus extinguishing lamp e1. Relay g also opens its contact 37, thus breaking the stick circuits for relays T and X. Lamps e4 and e5 are thereby extinguished. Relay J, however, continues energized by its stick circuit as previously traced.

In order to make certain that the front contacts of relay L will always open again when either of the branch paths around relay H1 opens, a branch path is provided around the winding of relay L, passing from wire 47, through wire 137, contact 138 of relay T, and contact 141 of relay X in multiple with contact 144 of relay W to wire 50.

I will next assume that the despatcher returns lever V2 to its normal or *n* position, de-energizing relays H1 and H2. With relay H2 de-energized, the stick circuit for relay J is opened at contact 92 of relay H2, and hence relay J is also de-energized.

If, now, a second westbound train approaches, de-energizing relay R2 while lever V2 is in its *n* position, relay L becomes energized by a circuit passing from battery Q4, through wires 124 and 125, contact 126 of relay R2, wire 127, contact 128 of relay P, wires 50 and 49, winding of relay L, wires 48 and 47, contact 135 of lever V2, wires 136, 33, 28, 22, 56, 55 and 132, contact 131b of relay H1, and wire 133 back to battery Q4. With relay L energized, relay

T becomes energized by its circuit previously traced.

Relay T, upon becoming energized, completes a second stick circuit passing from battery Q1, through wire 10, contact 37 of relay g, wires 38, 87 and 110, contact 114 of relay X, wire 99, contact 98 of relay T, winding of relay T, and wires 80, 43 and 22 to battery Q1. With relay T energized, approach lamp e5 is lighted by current passing through the stick circuit for relay T as just traced as far as contact 114 of relay X, thence through wire 100, contact 101 of relay T, wire 102, lamp e5, and wires 103, 33 and 28 back to battery Q1. After relay L becomes de-energized, relay T continues energized by its stick circuit, and hence approach lamp e5 continues lighted.

If, now, while a train is in section D—E, the despatcher should again reverse lever V2 to its *p* position for clearing arm S3, relay H1 and H2 become energized by the circuit as previously described except including, around contacts 51a and 52a of relays P and R2, respectively, a branch path through contacts 51b and 52b. Relay L also becomes energized as previously described, due to the closing of contact 76 of relay K which thereby completes for a brief period a branch path around the winding of relay H1. Relays X and J then also become energized by their circuits as previously traced.

I will now assume that with the apparatus modified as shown in Fig. 2, all parts are in their normal condition, that is, sections C—D and D—E are unoccupied, switch F is in its normal position, levers V1 and V2 are in their normal positions, and all signals are indicating "stop." With relay R2 energized, relay P is energized as previously described, and with all signals indicating "stop," relay N is energized by its circuit already traced. With relay N energized, slow-releasing relay U is energized by its circuit passing from battery Q3, through wire 166, contact 167 of relay N, wire 168, winding of relay U, and wire 169 back to battery Q3.

If, now, a westbound train approaches, de-energizing relay R2, relay L becomes energized by current passing from battery Q4, through wires 124 and 125, contact 126 of relay R2, wire 127, contact 128 of relay P, wires 73 and 163, winding of relay L, wires 162 and 190, contact 135 of lever V2, wires 191, 178, 23, 55 and 132, and contact 131b of relay H1 back to battery Q4. With relay L thus energized, relay T2 becomes energized by its circuit passing from battery Q1, through wires 172, 173 and 174, contact 182 of relay L, wire 183, winding of relay T2, and wires 177 and 178 back to battery Q1. Relay T2, upon becoming energized, completes its stick circuit passing from battery Q1, through wire 172, contact of push-but-

ton *b*, wire 184, contact 185 of relay T2, winding of relay T2, and wires 177 and 178 back to battery Q1. With relay T2 energized, approach lamp *e5* becomes lighted by 5 its circuit passing from battery Q1, through wire 172, contact of push button *b*, wire 184, contact 186 of relay T2, wire 187, lamp *e5*, and wire 171 back to battery Q1. When the despatcher has observed the indication of 10 lamp *e5*, he can de-energize relay T2 by opening the contact of push button *b*, and will thus extinguish lamp *e5*.

I will next assume that the despatcher reverses lever V2 to its *p* position for clearing arm S3. Relays H1 and H2 are then 15 energized by their circuit passing from battery Q1, through wire 160, contact 45 of lever V2, wire 161, winding of relay H2, wire 162, winding of relay L, wires 163 and 20 164, winding of relay H1, and wires 54, 55, 23 and 178 back to battery Q1. When arm S3 starts to clear and opens its contact 6, de-energizing relay N, a branch path, passing from wire 163, through wire 73, contact 25 74 of relay N, wire 75, and contact 79 of relay U to wire 23, is momentarily closed, permitting sufficient current to flow to operate relay L. Relay T1 is then energized by its circuit passing from battery Q1, through 30 wires 172, 173, and 174, contact 175 of relay L, winding of relay T1, and wires 176, 177 and 178 back to battery Q1. Relay T1, upon becoming energized, completes its 35 stick circuit passing from battery Q1, through wires 172 and 173, contact 179 of relay H2, wire 180, contact 181 of relay T1, winding of relay T1, and wires 176, 177 and 178 back to battery Q1. Although relay T2 will be momentarily energized by its 40 pick-up circuit, the despatcher can prevent its continued energization through its stick circuit, by opening the contact of push button *b*. With relay T1 energized, lamp *e4* will be lighted by its circuit passing from 45 battery Q1, through wires 172 and 173, contact 179 of relay H2, wire 180, contact 188 of relay T1, wire 189, contact 108 of lever V2, wire 109, lamp *e4*, and wire 171 back to battery Q1.

If, now, a westbound train de-energizes 50 relay R2, a branch path will be completed around the winding of relay H1 in the circuit shown in Fig. 2. This branch path passes from wire 163, through wire 73, contact 128 of relay P, wire 127, contact 126 of relay R2, wires 125 and 165, contact 131a of relay H1, and wire 132 to wire 55. With 55 this branch path completed, relay L is operated, causing lamp *e5* to be lighted as already described.

From the accompanying drawings, and from the foregoing descriptions of the operation of the apparatus comprising my invention for typical traffic movements and 60 conditions, the operation of the apparatus

for other traffic movements and conditions will be readily understood.

Although I have herein shown and described only two forms of remote control apparatus embodying my invention, it is understood that various changes and modifications may be made therein within the scope of the appended claims without departing from the spirit and scope of my invention.

Having thus described my invention, what I claim is:

1. In combination, a railway traffic governing device, a pair of conductors, a manually operable lever, an indication means, a relay for controlling said device, a circuit including said conductors and said relay, a branch path around said relay in said circuit and controlled by said device, means controlled by said lever for supplying said circuit with current for operating said relay, and means controlled by said lever for supplying to said branch path current for controlling said indication means.

2. In combination, a railway traffic governing device, a pair of conductors, a manually operable lever, means controlled by said lever for at times supplying said conductors with current for controlling the operation of said device, an indication means, means controlled by said governing device for supplying said pair of conductors with current for controlling the energization of said indication means, and means controlled by said lever for continuing the energization of said indication means.

3. In combination, a railway traffic governing device, a pair of conductors, a manually operable lever, a first indication relay, a second indication relay responsive only to current of greater magnitude than is necessary for the operation of said first relay, a circuit including said conductors and said first and second indication relays in series, means controlled by said lever for at times supplying said circuit with current for controlling the operation of said device and for operating said first indication relay but not of sufficient magnitude for operating said second indication relay, means controlled by said device for at times supplying said relays with current of sufficient magnitude to operate said second as well as said first relay, a stick relay having a pick-up circuit controlled by said second relay and having a stick circuit controlled by said first relay, and indication means controlled by said stick relay.

4. In combination, a railway signal, a pair of conductors, a manually operable lever, a relay for controlling the operation of said signal, a circuit including said relay and said conductors, means controlled by said lever for supplying said circuit with current for operating said relay, a branch

path around said relay in said circuit, means for completing said branch path when said signal changes to "proceed", an indication means, and means controlled by said lever for supplying current to said branch path for controlling said indication means.

5. In combination, a railway traffic governing device, a pair of conductors, an indication relay, a control circuit for said device including said relay and said conductors, means for at times supplying said circuit with current of sufficient magnitude to cause the operation of said device but of insufficient magnitude to operate said relay, means controlled by said device for at times supplying to said relay through said conductors a current of sufficient magnitude to operate said relay, a section of track adjacent said device, a stick relay having a pick-up circuit controlled by said indication relay and having a stick circuit controlled by traffic conditions in said section, and indication means controlled by said stick relay.

25 6. In combination with a railway traffic governing device, a pair of conductors, an indication relay, a control circuit for said device including said relay and said conductors, means for at times supplying said circuit with current of sufficient magnitude to cause the operation of said device but of insufficient magnitude to operate said relay, a first and a second section of railway track adjacent said device, means controlled by traffic conditions in said first section for at times supplying to said relay through said conductors a current of sufficient magnitude to operate said relay, a stick relay having a pick-up circuit controlled by said indication relay and having a stick circuit controlled by traffic conditions in said second section, and indication means controlled by said stick relay.

45 7. In combination, a railway traffic governing device, a contact so operated by said device as to be opened for a brief period during each movement of said device to one position or another, a track section adjacent said device, a track circuit for said section including a track relay, a conductor, an indication relay, a control circuit for said device including said device contact and a contact of said track relay as well as said conductor and the winding of said indication relay in series, means for at times supplying said circuit with current for operating said indication relay and for controlling the operation of said device, a slow release relay controlled by said indication relay and so constructed as to respond to the de-energized periods of said indication relay as caused by the opening of said track relay contact but not to respond to the de-energized periods of said indication relay as caused by the opening of said device contact,

an indication means controlled by said indication relay, and a second indication means controlled by said slow release relay.

8. In combination, a railway signal, a pair of conductors, a manually operable lever, a relay for controlling the operation of said signal, a circuit including said relay and said conductors, means controlled by said lever for supplying said circuit with current for operating said relay, a branch path around said relay in said circuit, a second relay controlled by a contact which is so operated by said signal as to be closed only when said signal indicates "stop," a slow release relay controlled by a front contact of said second relay, a back contact of said second relay and a front contact of said slow release relay connected in series in said branch path, an indication means, and means controlled by said lever for supplying said branch path with current for controlling said indication means.

9. In combination, a section of railway track, a signal for governing traffic movements into said section, a track circuit for said section including a track relay, an approach track section for said signal, a track circuit for said approach section including a track relay, a first indication relay, a second indication relay responsive only to current of greater magnitude than is necessary for the operation of said first indication relay, a pair of conductors, a control circuit for said signal including said conductors and said first and second indication relays in series, manually controlled means for at times supplying said circuit with current for causing said signal to indicate proceed and of sufficient magnitude to operate said first indication relay but not said second indication relay, means for operating said second indication relay when said signal indicates proceed, means for operating said second indication relay when said approach track relay becomes de-energized, a first and a second and a third stick relay, a slow release relay, a pick-up circuit for said first stick relay controlled by a front contact of said second indication relay, a stick circuit for said first stick relay including a front contact thereof and a back contact of said slow release relay in multiple with a back contact of said second stick relay as well as a source of current and controlled by a front contact of said first track relay, an operating circuit for said slow release relay controlled by back contacts of said first and second stick relays and by a front contact of said first track relay, a pick-up circuit for said second stick relay controlled by a back contact of said third stick relay and by front contacts of said first and second indication relays, a stick circuit for said second stick relay controlled by a front contact of said first indication

relay and by a front contact of said first track relay, a pick-up circuit for said third stick relay controlled by a front contact of said second stick relay and by a front contact of said first indication relay, a stick circuit for said third stick relay controlled by a front contact of said first indication relay, indication means controlled by a front contact of said second stick relay, and a second indication means controlled by a front contact of said first track relay and by a circuit including a front contact of said first stick relay and a back contact of said slow release relay in multiple with a back contact 15 of said second stick relay.

10. In combination, a railway signal, a relay for controlling said signal, an indication relay responsive only to current of greater magnitude than is necessary for the 20 operation of said control relay, a circuit including said control and indication relays in series, manually controlled means for supplying said circuit with current of sufficient magnitude to operate said control relay but 25 not said indication relay, a track section, a track circuit for said section including a track relay, a branch path controlled by said track relay and constituting a shunt around said control relay and thereby permitting 30 said manually controlled means to supply sufficient current through the winding of said indication relay to operate said indication relay, a signal relay energized when said signal indicates stop, a second track 35 section, a track circuit for said second section including a second track relay, a control circuit for said second track relay including a back contact of said control relay in multiple with a front contact of said second 40 track relay, a slow release stick relay, a pick-up circuit for said stick relay controlled by a front contact of said signal relay and by a front contact of said second track relay, a stick circuit for said stick relay controlled 45 by a front contact of said signal relay, a back contact of said stick relay included in said branch path, a second branch path in multiple with said control relay and with said first branch path and including a back 50 contact of said signal relay and a front contact of said stick relay, and indication means controlled by said indication relay.

11. In a traffic control system, a railway track switch, a control circuit for said switch 55 including an indication relay, a slow release relay having a pick-up circuit controlled by said indication relay, and indication means controlled by said slow release relay.

12. In combination, a railway track 60 switch, a control circuit for said switch including an indication relay, means controlled by said switch and means controlled by traffic conditions adjacent said switch respectively for controlling said circuit, a 65 slow release relay having a pick-up circuit

controlled by said indication relay, and indication means controlled by said slow release relay.

13. In combination, a railway track switch, a control circuit for said switch including an indication relay, means controlled by traffic conditions for at times opening said circuit, means controlled by said switch for at times momentarily opening said circuit, and indication means controlled by said indication relay and responsive to the open periods of said indication relay as caused by said traffic conditions but not responsive to the open periods of said indication relay as caused by said switch. 70

14. In combination, a railway track switch, a control circuit for said switch including an indication relay, means controlled by traffic conditions for at times opening said circuit, means controlled by said switch for at times momentarily opening said circuit, a slow release relay controlled by said indication relay and responsive to the open periods of said indication relay as caused by said traffic conditions but 85 not responsive to the open periods of said indication relay as caused by said switch, and indication means controlled by said slow release relay. 90

In testimony whereof I affix my signature. 95
JAMES J. VANHORN.
